(57) **CLAIM**

The ornamental design for a plug-in ready electronic reader and parts thereof, as shown and described.

DESCRIPTION

FIG. 1 is a front perspective view of the plug-in ready electronic reader showing our design;

FIG. 2 is a front view thereof;

FIG. 3 is a side view thereof;

FIG. 4 is an opposing side view of the side shown in FIG. 3;

FIG. 5 is a bottom end view thereof;

FIG. 6 is a top end view thereof; and,

FIG. 7 is a front perspective environmental view thereof illustrating the plug-in ready electronic reader in an exemplary clinical use environment.

The rear view is disclaimed in this embodiment.

The broken lines shown herein are for illustrative purposes only and form no part of the claimed design. The environmental view illustrates the plug-in ready electronic reader easily installed via direct plug in to a wall receptacle in a clinical environment.
